Primary Examiner—Stacia Cadmus(74) *Attorney, Agent, or Firm*—Alan G. Towner, Esq.; Pietragallo, Bosick & Gordon**CLAIM**

The ornamental design for sports ball wheel cover, as shown and described.

DESCRIPTION

FIG. 1 is a perspective view of sports ball whell cover, showing my new design;

FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 is a back view thereof; and,

FIG. 8 is a side view of the sports ball whell cover of FIG. 1, illustrating its mounting position on a wheel drawn in phantom lines.

The broken line showing of environment is for illustrative purposes only and forms no part of the claimed design.
